(57) **CLAIM**

The ornamental design for an image measuring device, as shown and described.

DESCRIPTION

FIG. 1 is a front, right-side, top perspective view of a first embodiment of the image measuring device;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a rear elevational view thereof; and

FIG. 7 is a bottom plan view thereof.

FIG. 8 is a front, right-side, top perspective view of a second embodiment of the image measuring device;

FIG. 9 is a front elevational view thereof;

FIG. 10 is a top plan view thereof;

FIG. 11 is a right-side elevational view thereof;

FIG. 12 is a left-side elevational view thereof;

FIG. 13 is a rear elevational view thereof; and,

FIG. 14 is a bottom plan view thereof.

The broken lines depict unclaimed portions of the image measuring device, and thus form no part of the claimed design.
